UNITED STATES PATENT OFFICE.

WILLIAM NOBLE, OF NORTHAMPTON, MASSACHUSETTS, ASSIGNOR, BY MESNE ASSIGNMENTS, TO PRO-PHY-LAC-TIC BRUSH COMPANY, OF NORTHAMPTON, MASSACHUSETTS, A CORPORATION OF MASSACHUSETTS.

BOXING MACHINE.

Application filed May 18, 1923. Serial No. 639,989.

This invention has for its object to provide a machine to receive from a spout or other delivery device elongated articles, such as tooth brush handles, and arrange them 5 in an orderly fashion in a box parallel with each other so that the next operation in the factory can be performed conveniently, or so that they may be fed directly from the box into another machine. Heretofore, 10 considerable hand labor has been necessary to accomplish this, since the handles fall from the spout into the box crosswise or in irregular positions making it necessary to rearrange them or straighten them out. 15 The machine embodying my invention provides a simple and effective device for accomplishing this result. In its preferred form, there is a box having movable partitions which separate it into temporary 20 compartments each of which is considerably narrower than the length of one of the objects to be received in it. The box is reciprocated transversely to the line of movement of the objects as they emerge 25 from the spout so that successive objects fall into separate compartments. Since the compartments are narrower than the length of the object, the article will not get crosswise or in a diagonal position. The reciprocating movement of the box also helps to jar them down into position parallel with each other. When the compartments in the 30 box are full, the box is taken from the machine and the partitions are removed, leaving the entire mass of objects in the box in perfect parallel arrangement ready to be fed to another machine.

In the accompanying drawings, I have shown my machine as designed for use in the manufacture of tooth brushes, the objects to be handled by the machine being tooth brush handles. It is to be understood, however, that the machine is not limited to use in this connection but is capable of 45 use for a large variety of purposes.

The invention will be fully understood from the following description when taken in connection with the accompanying drawings, and the novel features thereof will be pointed out and clearly defined in the claims at the close of this specification.

In the drawings:

Fig. 1 is a top plan view of a machine embodying the invention.

Fig. 2 is a front elevation of the machine 55 shown in Fig. 1.

Fig. 3 is an end view of the machine shown in Fig. 1.

Figs. 4 and 5 are details of the box.

Referring now to the drawings, at A is 60 shown the frame of the machine which is provided with a travelling bed B slidably mounted thereon. At C is shown (see Figs. 2 and 3) a spout down which the objects to be boxed are fed. In these figures a 65 tooth brush handle D is seen coming down the spout.

The bed B reciprocates back and forth in the direction of the arrows indicated in Fig. 1, being slidable in guides 10 on the frame 70 of the machine. The line of movement of the travelling bed is, in general, transverse to the line of movement of the brush handles or other objects down the spout. Mounted on the travelling bed is a base 11 75 which is provided with edge pieces or guides 12 adapted to position a box composed of two parts 13 and 14 (see also Figs. 4 and 5). The lower part 13 of the box has four walls and a bottom, and the top part 14 80 comprises a frame forming an upward extension of the side walls of the bottom half of the box and is provided with a series of partitions 15 which extend downward into the lower part of the box. The whole 85 forms a box having compartments 6, but the partitions 15 can be removed simultaneously by lifting up the frame 14 so that the entire mass of objects in the box will then be unseparated by partitions but will be 90 arranged parallel with each other. The upward extension of the side walls permits the bottom of the box to be filled full and all the objects contained in it to be in parallel position.

The travelling bed B is given a reciprocating movement with a stroke long enough to carry the box so that, at the opposite ends of the stroke, the respective end compartments will be under the spout.

The mechanism by which the box is reciprocated will now be described. At 18 is shown a shaft having thereon a driving pulley 19 and a worm 20 which engages worm teeth in the edge of a horizontal gear 21 mounted on a stud 22. On the upper face of the worm gear 21 are gear teeth over a portion *a* which is about 180 degrees, the

- remainder *b* being cut away. It will therefore be seen that the upper surface of the worm gear 21 constitutes a semi-circular rack. Above the semi-circular rack is a horizontal shaft 23 having two pinions, 24 and 25, respectively. The pinion 25 also engages on its upper surface a straight rack 26 secured to the lower side of the travelling bed B.
- 10 From the foregoing it will be seen that the main shaft 18, through the worm 20, rotates the semi-circular rack on the worm gear 21 continuously in the same direction, and that the rack teeth drive the two pinions 24 and 25 as they pass beneath them. The shaft 23 will therefore be revolved alternately in opposite directions, and this will cause the travelling bed and box thereon to reciprocate with substantially uniform speed back and forth under the lower end of the spout C.
- 15 As the handles or other elongated objects fall out of the end of the spout C, they drop into whichever compartment 6 is at that moment underneath the spout. It makes no difference if they happen to strike the edge of the partition, since they will not remain there. As the box travels back and forth underneath the spout at substantially uniform speed, the objects are distributed substantially uniformly in the several compartments. The objects tend to arrange themselves substantially parallel with each other, since the compartments are considerably narrower than the length of the handles and since there is little vibration when the box changes direction at the end of the stroke.
- 20 When the box is full, it is removed from the machine, and the frame 14 bearing the several partitions is lifted off leaving the handles in a single mass in the box, the parallelism being undisturbed. The frame 14 furnishes a space above each compartment of the box so that the box can be filled practically level with the top edge.
- 25 While I have described the use of a semi-circular rack, as the reversing mechanism by which the bed and box thereon are reciprocated past the spout, I do not limit myself to this form of reversing mechanism since other mechanisms can be employed if preferred. I find, however, that the mechanism described is simple, inexpensive to construct, and will operate continuously for long periods of time without attention.

What I claim is:

1. A machine for delivering elongated articles and arranging them in parallel relation comprising, in combination, means for delivering said articles in the direction of their length, a box arranged to receive said articles and having partitions disposed substantially parallel to the direction of delivery thereof, and means for moving said box

in a direction transverse to said direction of delivery as said articles are delivered thereto.

2. A machine for delivering elongated articles and arranging them in parallel relation comprising, in combination, means for delivering said articles singly and in a single path in the direction of their length, a box arranged to receive said articles and having partitions disposed substantially parallel to the direction of delivery thereof, and means for moving said box in a direction transverse to said direction of delivery as said articles are delivered thereto.

3. A machine for delivering elongated articles and arranging them in parallel relation comprising, in combination, means for delivering said articles in the direction of their length, a box arranged to receive said articles and having partitions disposed substantially parallel to the direction of delivery thereof, and means for moving said box with a substantially uniform motion in a direction transverse to said direction of delivery as said articles are delivered thereto.

4. A machine for delivering elongated articles and arranging them in parallel relation comprising, in combination, means for delivering said articles in the direction of their length, a box arranged to receive said articles and having partitions disposed substantially parallel to the direction of delivery thereof, and means for moving said box back and forth in a direction transverse to said direction of delivery as said articles are delivered thereto.

5. A machine for delivering elongated articles and arranging them in parallel relation comprising, in combination, a spout for delivering said articles, a box arranged to receive said articles from said spout and having partitions substantially parallel with the latter, and means for moving said box transversely of said spout as said articles are delivered.

6. A machine for delivering elongated articles and arranging them in parallel relation comprising, in combination, a spout for delivering said articles, a box arranged to receive said articles from said spout and having partitions substantially parallel with the latter, and means for moving said box back and forth transversely of said spout as said articles are delivered.

7. A machine for delivering elongated articles and arranging them in parallel relation comprising, in combination, a spout for delivering said articles, a box arranged to receive said articles from said spout and having partitions substantially parallel with the latter, and means for moving said box back and forth with a substantially uniform motion transversely of said spout as said articles are delivered.

8. A machine for delivering elongated articles and arranging them in parallel relation comprising, in combination, a spout for delivering said articles, a box arranged to receive said articles from said spout and having partitions substantially parallel with the latter, a straight rack to move said box transversely of said spout, a shaft carrying two pinions one of which meshes with said rack, a semi-circular rack engaging said pinions alternately, and means for rotating

said semi-circular rack continuously in one direction.

9. In a machine of the character described, the combination with means for delivering articles, of a receptacle support and means to reciprocate the support transversely of the direction of article delivery with a substantially uniform motion. 15

In testimony whereof I affix my signature.

WILLIAM NOBLE.
